UNITED STATES PATENT OFFICE.

THOMAS WILLIAMS AND WILLIAM A. PRESTON, OF PRINCETON, INDIANA;
SAID WILLIAMS ASSIGNOR TO SAID PRESTON.

GATE.

SPECIFICATION forming part of Letters Patent No. 291,858, dated January 8, 1884.

Application filed June 5, 1883. (No model.)

To all whom it may concern:

Be it known that we, THOMAS WILLIAMS and WILLIAM A. PRESTON, citizens of the United States, residing at Princeton, in the county of Gibson and State of Indiana, have invented certain new and useful Improvements in Gates, of which the following is a specification, reference being had therein to the accompanying drawings.

10 This invention relates to certain improvements in gates; and it has for its object to provide improved mechanism whereby the gate may be opened or closed from either side and automatically unlocked and locked by the operation of opening and closing, as more fully hereinafter specified. These objects we attain by the means illustrated in the accompanying drawings, in which—

Figure 1 is a perspective view of our improved gate; Fig. 2, a detailed sectional view of a portion of the gate, showing the locking mechanism. Fig. 3 is a perspective view of the sliding block and bolt.

The letters A B C indicate the gate-posts, the posts A and B supporting the rails D, on which the gate travels, and the post C being so located that the gate can close against it. The gate consists of a series of parallel bars, E, connected by means of the vertical parallel bars F, and arranged to slide upon the rails D, before mentioned.

The letter G indicates a board secured to the rails D, just opposite the post B. The said board is slotted, as indicated by the letter C', the slot serving as a guide, in which slides a grooved block, H. To the upper end of the block is secured one end of a link, I,

which is connected to the adjacent ends of the levers K by suitable connections. These levers are fulcrumed to a cross-bar, L, secured 40 to the post B near the top, and extend to each side of the gate. To the block is pivoted one end of a rod, M, which at its lower end is pivoted to the lower rail of the gate, as shown. This rod serves to operate the gate as the 45 block is elevated or depressed by the levers. The upper rail of the gate is notched, as shown, at two points, into which notches the bolt N falls, when the gate is fully opened or closed, securely locking it in position. 50

In operation the gate is carried fully to either side by the momentum given it by the initial movement imparted by the lever.

Having thus described our invention, what we claim, and desire to secure by Letters Patent, is—

The combination of the parallel bars and their supporting-posts, the gate adapted to slide thereon, the slotted board and sliding block and bolt adapted to sit in notches in the 60 gate, the levers connected to said block, and the pivoted rod connecting the block and gate, the whole arranged to operate substantially in the manner specified.

In testimony whereof we affix our signatures 65 in presence of two witnesses.

THOMAS WILLIAMS.
WILLIAM A. PRESTON.
